(57) CLAIM

The ornamental design for a skort as shown and described.

DESCRIPTION

FIG. 1 is a front elevation view of a first embodiment of a skort in a first configuration;

FIG. 2 is a rear elevation view of the skort of FIG. 1;

FIG. 3 is a left side view of the skort of FIG. 1;

FIG. 4 is a right side view of the skort of FIG. 1;

FIG. 5 is a top plan view of the skort of FIG. 1;

FIG. 6 is a bottom plan view of the skort of FIG. 1;

FIG. 7 is a front elevation view of the skort of FIG. 1 in a second configuration;

FIG. 8 is a rear elevation view of the skort of FIG. 7;

FIG. 9 is a left side view of the skort of FIG. 7;

FIG. 10 is a right side view of the skort of FIG. 7;

FIG. 11 is a front elevation view of a second embodiment of a skort in a first configuration;

FIG. 12 is a rear elevation view of the skort of FIG. 11;

FIG. 13 is a left side view of the skort of FIG. 11;

FIG. 14 is a right side view of the skort of FIG. 11;

FIG. 15 is a top plan view of the skort of FIG. 11;

FIG. 16 is a bottom plan view of the skort of FIG. 11;

FIG. 17 is a front elevation view of the skort of FIG. 11 in a second configuration;

FIG. 18 is a rear elevation view of the skort of FIG. 17;

FIG. 19 is a left side view of the skort of FIG. 17; and,

FIG. 20 is a right side view of the skort of FIG. 17.

The evenly broken lines (dash-dash lines) shown in the Figures are only for illustrative purposes to show portions of the skort that form no part of the claimed invention.

1 Claim, 20 Drawing Sheets
